(57) **CLAIM**

The ornamental design for a water collecting pipe for filtering device, as shown and described.

DESCRIPTION

FIG. 1 is a perspective view of a water collecting pipe for filtering device, showing my new design;

FIG. 2 is a front elevational view thereof, the rear elevational view being a mirror image thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is an enlarged view of the section 7-7 in FIG. 2;

FIG. 8 is an enlarged cross-sectional view taken along line 8-8 in FIG. 3 within the section 7-7 in FIG. 2; and,

FIG. 9 is an enlarged cross-sectional view taken along line 9-9 in FIG. 7.

The dashed broken lines show portions of the water collecting pipe for filtering device that form no part of the claimed design. The dot-dash-dot broken lines define the bounds of the claimed design and form no part thereof.
